Primary Examiner — Wendy L Arminio*Assistant Examiner* — Maheen Khurshid(74) *Attorney, Agent, or Firm* — Birch, Stewart, Kolasch & Birch, LLP(57) **CLAIM**

The ornamental design for a tube, as shown and described.

DESCRIPTION

FIG. 1 is a right side view of a tube showing my new design; FIG. 2 is a left side view thereof;

FIG. 3 is a front view thereof;

FIG. 4 is a rear view thereof;

FIG. 5 is a bottom view thereof; and,

FIG. 6 is a perspective view thereof.

The dash-dash broken lines depict portions of the claimed design that form no part of the claimed design. The dash-dot-dash broken lines illustrate a boundary of the design that form no part of the claimed design.
